UNITED STATES PATENT OFFICE.

WILLIAM W. LOWREY, OF BALTIMORE, MARYLAND.

DESIGN FOR A BOTTLE.

SPECIFICATION forming part of Design No. 19,182, dated June 25, 1889.

Application filed May 9, 1889. Serial No. 310,145. Term of patent 14 years.

To all whom it may concern:

Be it known that I, WILLIAM W. LOWREY, a citizen of the United States, residing in the city of Baltimore and State of Maryland, have 5 invented and produced a new and original Design for a Bottle, of which the following is a specification, reference being made to the accompanying drawings, forming a part hereof.

Figure 1 is a side elevation of the new design, and Fig. 2 an end or edge elevation of the same. Fig. 3 is a top view of the bottle.

According to my design the exterior shape of the bottle is as follows: The bottom A is a symmetrical oval or ellipse. The sides B spring from the bottom at a right angle, are straight in the direction of their length and parallel to where the shoulder C begins, which makes the body of the bottle of a common size and shape of cross-section throughout its 20 entire length. The upper part a of the shoul-

der is spheroidal, and the base of the shoulder b, which joins the upper part of the shoulder to the sides B, pyramidoidal.

The neck D of the bottle is of the usual shape, and provided, as is common, with a 25 band c at its upper end.

What I claim is—

A design for a bottle, which consists of a bottom which is a symmetrical oval or ellipse, sides, which spring from the bottom at a right 30 angle, are parallel and straight throughout their length, and a shoulder the upper part of which is spheroidal and its lower part, which unites with the sides, pyramidoidal, substantially as described and shown.

WILLIAM W. LOWREY.
